[57] CLAIM

The ornamental design for a desk telephone set, as shown and described.

DESCRIPTION

FIG. 1 is a front, top and right side perspective view of a desk telephone set showing our new design;

FIG. 2 is a top plan view thereof;

FIGS. 3 and 4 are, respectively, front and rear elevational views thereof;

FIGS. 5 and 6 are, respectively, left and right side elevational views thereof;

FIG. 7 is a bracketed top plan view of the stand and a bottom plan view of the receiver of the set, shown in associated relationship;

FIGS. 8 and 9 are, respectively, left and right side elevational views of the stand alone; and

FIG. 10 is a rear elevational view of the stand alone.

FIG. 1

FIG. 2

FIG. 3

FIG. 4
